UNITED STATES PATENT OFFICE.

JESSE E. GEISSINGER, OF SHALER TOWNSHIP, NEAR MILLVALE, ALLEGHENY COUNTY, PENNSYLVANIA.

ATTACHMENT FOR CLOTHES-WRINGERS.

1,365,907.

Specification of Letters Patent.

Patented Jan. 18, 1921.

Application filed June 14, 1920. Serial No. 388,871.

To all whom it may concern:

Be it known that I, JESSE E. GEISSINGER, a citizen of the United States, residing in Shaler township, near Millvale, in the county of Allegheny and State of Pennsylvania, have invented certain new and useful Improvements in Attachments for Clothes-Wringers; and I do declare the following to be a full, clear, and exact description of the invention, such as will enable others skilled in the art to which it appertains to make and use the same.

This invention relates to clothes-wringers broadly, but more specifically to an attachment therefor, the purpose of this attachment being to feed the clothes between the press-rolls, thus enabling the operator to do this work effectively and obviate the necessity of using the hands as is ordinarily done, which custom oftentimes causes the operator's fingers to get caught between the rollers and severely injured. An attachment of this kind is especially, although not necessarily, designed for use in connection with power driven clothes-wringers.

Another object of the invention is to provide a device of this kind which may be applied on conventional types of wringers by inexperienced persons, it necessitating no structural changes whatsoever of the wringer.

A further object of the invention is to generally improve upon devices of this character by providing one of extreme simplicity, durability, and strength, which is highly effective in use, inexpensive to manufacture, and easy to manipulate, it being provided with means for automatically moving it out of the way when it is not in use.

Other objects and advantages of the invention will be apparent during the course of the following description.

In the accompanying drawings forming a part of the specification and in which like numerals are employed to designate like parts throughout the same:

Figure 1 is an elevational view of a conventional type of clothes-wringer equipped with an attachment constructed in accordance with my invention.

Fig. 2 is a sectional view taken on the plane of the line 2—2 of Fig. 1, looking in the direction of the arrows, and showing the position that my improved feeder takes when it is out of use.

Fig. 3 is a view like Fig. 2 showing the manner of using the device and the position which it takes when it is effective.

In carrying out my invention I employ a member of arcuate shape which I pivotally mount on the wringer adjacent the upper press-roller, this member being of a size to permit its free longitudinal edge to be swung down between the rollers for forcing the clothes between them, thus obviating the necessity of performing this work with the hands as is ordinarily done.

In the drawings, wherein for the purpose of illustration is shown a preferred embodiment of my invention, the numeral 1 designates a conventional type of clothes-wringer which includes a pair of press-rolls 2, and a feed-board 3, which parts are of the usual construction and arrangement.

My invention resides in the construction and arrangement of a manually operated member for engaging and forcing the clothes between the rollers 2. As before stated, the device is in the form of an attachment. It comprises a pair of bearings 4 which are adapted to be secured upon the uprights of the wringer-frame adjacent to, and slightly above the upper press-roller. Associated with and journaled in these bearings is a rock-shaft 5, provided at its opposite ends with journals 6 which are rotatably mounted in said bearings. In addition to this, the shaft includes a crank-arm 7, the purpose of which will be hereinafter described. If desired the major portion of this rock-shaft may be non-circular to permit a clothes feeding member to be effectively secured thereto. This member may be of any suitable form, but I prefer to employ a semi-circular plate 10 for the purpose, the same being secured at one of its ends to the rock-shaft, while its opposite free longitudinal edge is disposed in close proximity to the press-rollers and is adapted to be swung down and between the press-rollers for feeding a piece of clothing C between these rollers.

If desired this plate may be provided with a handle 11 so that it may be more easily and readily operated. It is desirable to have this feed member move to ineffective position 105 when the device is out of use. To this end I employ a coiled spring 12, which is connected at one of its ends to the crank arm 7 and at its opposite end to the wringer-frame 1.

In use the device is applied on the intake side of the wringer at a point just above the upper press-roller so that the effective edge of the feed member 10 may be moved 5 downwardly to coact with the rollers in the manner illustrated in Fig. 3. After the device is in place, the clothing C may be placed upon the inclined board 3 and the end of the clothing forced up into close 10 contact with the press-rolls as shown in Fig. 2. Then, the handle 11 may be gripped and the plate 10 moved downwardly and inwardly until its free longitudinal edge comes into engagement with the clothes. 15 With a further outward push, the clothes may be forced between the rolls enough to cause them to be gripped by the latter. As soon as the press-rolls take hold of the clothes the handle 11 may be released, and 20 the spring 12 will return the member 10 to ineffective position, in which position it is entirely out of the way and will not interfere with the work of the press-rolls.

An attachment of this nature is especially 25 designed for use in connection with power operated wringers, which type of wringers are more apt to draw the operator's fingers between the press-rolls and mash them. Employment of my device will protect the 30 fingers of the operator, and will cause the press-rolls to obtain a more effective grip on the clothing. The attachment is simple in construction, easy to operate, will absolutely prevent injury to an operator's fingers, and it is inexpensive to both the manufacturer and the user. Also, due to its 35 simplicity, the attachment may be applied by inexperienced persons. Furthermore, due to the employment of the coiled spring, the feed member is automatically moved to ineffective position which is a highly desirable feature.

It is thought that the foregoing description taken in connection with the accompanying drawings is sufficient to enable persons skilled in the art to which this invention relates, to obtain a clear understanding of the same, therefore, a more prolonged description is deemed unnecessary.

50. It is to be understood that the form of my invention herein shown and described is to be taken as a preferred form of the same, and that various minor changes in the shape, size, and arrangement of parts may

be resorted to without departing from the 55 spirit of the invention or the scope of the subjoined claims.

I claim:

1. The combination with a clothes wringer including a pair of press-rollers, of a shaft 60 rotatably mounted on said wringer and provided with a crank arm, an arcuate feed-plate secured on the shaft, one of its longitudinal edges being in a position to be swung between the rollers for forcing the clothes 65 between the latter, and a spring connected to the crank-arm and wringer for moving the plate to ineffective position.

2. An attachment for clothes-wringers comprising a shaft to be rotatably mounted 70 on the wringer, the same including a crank-arm, a feed plate carried by the shaft, and springs for connection to the wringer and crank-arm to automatically move the plate to ineffective position.

75 3. The combination with a clothes-wringer including a pair of press-rolls; of a shaft rotatably mounted on the wringer adjacent the upper press roll, an arcuate feed plate having one of its ends secured on the shaft 80 to position its opposite edge in a position to force the clothes between the rolls, and means to retain the plate normally in ineffective position.

4. The combination with a clothes-wringer 85 including a pair of press-rolls and a feed-board leading thereto; of bearings secured to said wringer, a shaft including a crank arm and journals mounted in said bearings, an arcuate feed-plate fastened at one of its 90 edges to said shaft, the opposite edge being arranged in a position to be swung against the clothes to force them between the rolls, and a coiled spring secured to the wringer and crank arm to move the plate to ineffective position when it is out of use.

95 5. An attachment for clothes-wringers comprising bearings for connection to a wringer, a shaft to be journaled in the bearings, said shaft being provided with a crank 100 arm, a feed-plate carried by the shaft, and a coiled spring connected to the crank arm, its opposite end to be connected to the wringer.

105 In testimony whereof I have hereunto set my hand.

JESSE E. GEISSINGER.
